UNITED STATES PATENT OFFICE.

HYMON HART SIMMONS, OF SIMMONSVILLE, MISSISSIPPI.

DEVICE FOR HOISTING WELL-BUCKETS.

SPECIFICATION forming part of Letters Patent No. 658,871, dated October 2, 1900.

Application filed July 13, 1900. Serial No. 23,523. (No model.)

To all whom it may concern:

Be it known that I, HYMON HART SIMMONS, a citizen of the United States, residing at Simmonsville, in the county of Pike and State 5 of Mississippi, have invented a new and useful Device for Hoisting Well-Buckets, of which the following is a specification.

This invention relates to devices for hoisting well-buckets and the like; and the object 10 of the same is to provide simple and effective means for elevating buckets of an elongated form used in small-bore wells with ease by a minimum amount of applied power and to have the several parts under control for adjustment or regulation of movement by a single operator.

The invention consists in the construction and arrangement of the several parts, which will be more fully hereinafter described and 20 claimed.

In the drawings, Figure 1 is a sectional side elevation of a device for hoisting well-buckets or the like embodying the features of the invention. Fig. 2 is a partial longitudinal 25 section of the device shown by Fig. 1, showing the inner portion of the operating mechanism. Fig. 3 is a transverse vertical section through the winding-drum and mechanism in connection therewith.

Similar numerals of reference are employed 30 to indicate corresponding parts in the several views.

The numeral 1 designates a well structure including a roof 2 and a platform 3. Suspended from the ridge of the roof and depending over the location of the well-curb below is a pulley 4, through which is run a rope or cable 5, leading into the well and attached to the well-bucket and also extending to a 35 drum 6, mounted in a supplemental casing 7, fixed on the platform 3 at one end of the well structure. This drum comprises opposite heads 8 and 9, connected by bars 10, with spaces between them for forming an anti- 40 slipping winding-surface for the said rope or cable. The head 8 has a central socket 11 in the outer portion thereof with an angular opening therein, in which is fitted the inner angular end 12 of a stub-shaft 13, which ro- 45 tatably extends through a metallic box 14 in the upper portion of one side 15 of the casing 7 and also through an outwardly-projecting

bearing 16 at the rear end of a bracket-plate 17, secured on the outer surface of said side. The said bracket is shown in full and dotted 55 lines in Fig. 1 and serves to strengthen the entire structure and particularly resists the strain exerted by the drum, and on the shaft 13 between the outer face of the head 8 and the inner side of the adjacent part of the cas- 60 ing a flange 18 is formed to always keep the said drum-head in proper spaced relation to the casing. The opposite head 9 also has a central socket 19 in its outer face to receive the end of an adjusting screw-bolt 19, having an outer 65 angular head 20 and a jam-nut 21, with an operating-wing, and by this means the drum may be adjusted at will to regulate its sensitiveness and to take up wear. On the outer end of shaft 13 a pinion 22 is secured and is in 70 continual mesh with a larger driving-gear 23, mounted on the outer end of stub-shaft 24, carried by the opposite or front end of the said bracket, the said gear having a crank- 75 handle 25, which, it will be observed, is located at the inner end of the said casing. Both the gear and pinion have their axes in the same horizontal plane and pivotally mounted at one end on one of the corner-posts of the well structure, as shown by Fig. 2, and projecting inwardly close to the inner surface of 80 the side of the casing on which the said gear and pinion are mounted is a horizontally-disposed brake-lever 26, having an intermediate deflection 27 and a bearing-plate 28 to contact with the rim of the drum-head 8, and thus control the movement of the said drum. The inner engageable end of the said lever is located close to the crank-handle 25 for easy 85 reach and quick operation, and secured to the said lever for movement therewith is a metallic strap 29, having its upper extremity loosely bent over the upper edge of the side 15, as at 30, and formed with a hook 31, to engage and operate a gravity-pawl 32, pivoted 90 at its outer end to the upper portion of said side and having its inner reduced end disposed to engage the teeth of the said pinion 22 to prevent backlash or movement of the drum in winding the rope or cable thereon. 95

The disposition of the driving-gear and pinion meshing therewith in the manner shown obstructs the tendency of said mechanism to slip, and the function of the connec-

tion between the pawl and brake-lever is to provide for releasing the said pawl and simultaneously have means in the hand of the operator to control the run-off of the rope or cable from the drum and the descent of the bucket into the well without requiring the separate arrangement and manipulation of unconnected similar parts, and by locating the crank-handle of the driving-gear and the 10 engaging end of the brake-lever adjacent to each other the raising and lowering operations of the well-bucket can be conveniently and fully controlled.

Many advantages will become apparent as 15 existing in the improved structure by the use of the same, and such changes as fall within the scope of the invention will be adopted.

Having thus described the invention, what is claimed as new is—

20 The combination with an elevating rope or cable, of an adjustable drum, a stub-shaft projecting from one end thereof, a pinion on

said shaft, a driving-gear having a crank-handle, the said gear being in continual mesh with the pinion and both the gear and pinion having their axes in the same horizontal plane, a gravitating pawl to take into the teeth of the pinion, a brake-lever having its inner end adjacent the crank-handle of the driving-gear and said brake arranged to contact with one end of the drum, and a strap attached to the said lever and having an upper hooked extremity to engage the pawl and simultaneously throw the latter out of the teeth of the pinion when the brake-lever 35 is operated to contact with the drum end.

In testimony that I claim the foregoing as my own I have hereto affixed my signature in the presence of two witnesses.

HYMON HART SIMMONS.
